United States Patent Office

Des. 176,122
Patented Nov. 22, 1955

176,122

TRAILER BODY

Wilbur D. Hockensmith, Jr., Irwin, Pa.

Application March 4, 1955, Serial No. 34,869

Term of patent 14 years

(Cl. D14—3)

Fig. 1

Fig. 2

Fig. 3

Fig. 4

Fig. 1 is a side view of a trailer body embodying my new design;

Fig. 2 is a plan view thereof;

Fig. 3 is a view of the front end of the body; and

Fig. 4 is a view of the rear end of the body.

The chassis, wheels and fragmentary portion of a tractor, all shown by means of dotted lines, are only disclosed for illustrative purposes.

I claim:

The ornamental design for a trailer body, as shown and described.
